UNITED STATES PATENT OFFICE.

JULES MAIRE, OF ARGENTEUIL, FRANCE, ASSIGNOR TO ALPHONSE EMILE VERGÉ, OF VINCENNES, FRANCE.

GELATIN EXPLOSIVE.

1,128,471.

Specification of Letters Patent. Patented Feb. 16, 1915.

No Drawing.

Application filed July 22, 1913. Serial No. 780,479.

To all whom it may concern:

Be it known that I, JULES MAIRE, a citizen of the Republic of France, residing at Argenteuil, in the Department of Seine-et-Oise, France, have invented a new and useful Gelatin Explosive, of which the following is a specification.

In my prior Patent No. 1,124,496, dated Jan. 12, 1915, there is described the manufacture of a new group of liquid nitro-toluenes, together with the relation thereof to explosives generally.

The present invention has reference to this same group of nitro compounds, but is specifically directed to the production of a new gelatin explosive which is obtained therefrom. As a complete description of these liquid nitro-toluenes is contained in the above-identified application, it is considered sufficient for present purposes to state that they are of two classes or kinds, both of which are obtained by the nitration of initial mixtures of mononitro-toluenes containing essentially from 45 to 85 per cent. of meta-mononitro-toluene, the first class being composed by liquid compounds which are exactly binitrated, while the second class is comprised by supernitrated liquid compounds. The liquid compounds of the first class may be obtained, for example, by mixing with the usual nitrating mixtures of sulfuric and nitric acids, mixtures of mono-nitro-toluenes of the character just stated, and those of the second class may be obtained, for example, by dissolving one of the liquid binitrotoluenes of the said first class in a definite quantity of solid trinitrotoluene.

In carrying out the invention, that is to say, in producing the improved gelatin explosive, an oxidizing-salt in powdered form is incorporated with gelatin obtained by dissolving collodion cotton in one of the above-named nitro-toluenes, the latter being used either alone or mixed with nitroglycerin. Chlorates, perchlorates, nitrates, or mixtures thereof, may be utilized as the oxidizing salts, with the obvious exception, however, of a mixture of chlorates with perchlorate of ammonia, the danger of which is well known.

For the nitro-toluenes, I make use of one of those contained in the second class above

referred to, in preference to those of the first class, owing to the greater percentage of nitrogen in the latter, and among those contained in the aforesaid second class I especially prefer the ones which have the lowest point of fusion, in order to obtain a gelatin which will freeze only with the greatest possible difficulty. The most suitable compound which I have found for the purpose stated is that produced by dissolving 20-25 per cent. of solid trinitrotoluene in liquid binitrotoluene obtained by nitration of a mixture of about 60 parts of meta-mononitrotoluene and 40 parts of ortho-mononitrotoluene, the resultant liquid compound containing approximately 16 per cent. of nitrogen and freezing at about -26° C. Owing to the character of the liquid nitro-toluenes which I employ, the gelatin explosives obtained by means thereof will have the characteristic property of retaining their plasticity and stability for an indefinite period, during storage, at temperatures varying from -30° C. to +40° C. or even +50° C., or, in other words, to the highest temperatures to which they are exposed under actual working conditions in mines. Moreover, they are but very slightly sensitive to mechanical action, while, on the other hand, their power approaches that of the high explosives used in blasting. If it is desired to obtain explosives of even higher power which are comparable, if not superior, to the most powerful dynamites, but which, on the other hand, have the important advantages thereover of lower cost of manufacture, less sensitiveness to mechanical action, and, in particular, greater resistance to cold, the liquid nitro-toluenes may be mixed with suitable quantities of nitroglycerin, the resultant compounds having a greatly increased sensitiveness to primers. In such case, as in that first described, the nitro-toluene which has proved most effective is the one obtained by dissolving solid trinitrotoluene in liquid binitrotoluene in the manner and substantially in the proportions previously explained, and it has been found from experiments that a mixture of 30 parts of this particular liquid nitro-toluene and 70 parts of nitroglycerin does not freeze even at -35° C.

The following are given as examples of the improved gelatin explosive:

	A	B
5 The afore-mentioned, preferred nitro-toluene compound	17.0	15.5
Nitroglycerin	40.0	36.8
Collodion cotton	5.0	4.7
10 Ammonium perchlorate	38.0	—
10 Sodium chlorate	—	43.0
Total	100.0	100.0

Subjected to the Trauzl test, the compound A gives, on explosion, a volume of 622 cc., and the compound B a volume of 488 cc., while the height of explosion for a falling weight of 2 kg. is 35 cm. for the compound A, and 40 cm. for the compound B.

20 I claim:

1. A gelatin explosive comprising an oxidizing salt; nitrocellulose; and a solution of solid trinitrotoluene in liquid binitrotoluene obtained by the nitration of a mixture containing essentially from 45 to 85 per cent. of meta-mononitrotoluene with the other isomeric mononitrotoluenes, the aforesaid liquid binitrotoluene being a true liquid having a sharply-defined, constant melting point and characterized by its freedom from mononitro derivatives and from loss of weight when heated for a period of twenty-four hours to 60° C., and by the quantity of nitrogen which it contains remaining the same before and after such heating.

25 2. A gelatin explosive comprising an oxidizing salt; nitroglycerin; nitrocellulose; and a solution of solid trinitrotoluene in liquid binitrotoluene obtained by the nitration of a mixture containing essentially from 45 to 85 per cent. of meta-mononitrotoluene with the other isomeric mononitrotoluenes, the aforesaid liquid binitrotoluene being a true liquid having a sharply-defined, con-

stant melting point and characterized by its freedom from mononitro derivatives and from loss of weight when heated for a period of twenty-four hours to 60° C., and by the quantity of nitrogen which it contains remaining the same before and after such heating.

3. A gelatin explosive comprising a liquid nitrotoluene produced by dissolving solid trinitrotoluene in the product obtained by nitrating a mixture of 60 parts of meta-mononitrotoluene and 40 parts of ortho-mononitrotoluene; nitrocellulose; and an oxidizing salt, the aforesaid liquid binitrotoluene being a true liquid having a sharply-defined, constant melting point and characterized by its freedom from mononitro derivatives and from loss of weight when heated for a period of twenty-four hours to 60° C., and by the quantity of nitrogen which it contains remaining the same before and after such heating.

4. A gelatin explosive composed of 70 parts of nitroglycerin; 30 parts of a solution of solid trinitrotoluene in liquid binitrotoluene obtained by nitrating a mixture of 60 parts of meta-mononitrotoluene and 40 parts of ortho-mononitrotoluene; nitrocellulose; and an oxidizing salt, the aforesaid liquid binitrotoluene being a true liquid having a sharply-defined, constant melting point and characterized by its freedom from mononitro derivatives and from loss of weight when heated for a period of twenty-four hours to 60° C., and by the quantity of nitrogen which it contains remaining the same before and after such heating.

In testimony whereof I have signed this specification in the presence of two subscribing witnesses.

JULES MAIRE.

Witnesses:

EMILE LEDRET,
LUCIEN MEMMINGER.
